BOOK BINDING

William David Price, Los Angeles, Calif.

Application March 31, 1939, Serial No. 265,327

1 Claim. (Cl. 281—21)

This invention relates to book binding, and has particular reference to an improved means for binding books, particularly those from which the binding has become detached and which require 5 to be rebound.

An important object of the present invention is to provide improved means for binding books which is simple in character, which may be applied by unskilled persons, which does not require 10 that any of the parts be sewed or stitched, which will effectively withstand hard usage, and which will allow the book to lay flat when opened.

With the above and other objects in view as will be hereinafter apparent, the invention consists in 15 certain novel features and details of construction, and certain combinations of parts hereinafter more fully described, illustrated in the accompanying drawings and claimed.

In the accompanying drawings: 20 Figure 1 is a perspective view showing the leaves of a book prepared in accordance with the first step in carrying out the present invention.

Figure 2 is a view similar to Figure 1 illustrating succeeding steps in carrying out the present 25 invention.

Figure 3 is a still further perspective view illustrating still another succeeding step in carrying out the present invention.

Figure 4 is a perspective view illustrating still 30 another succeeding step in carrying out the present invention.

Figure 5 is a perspective view of the completed book in opened condition; and

Figure 6 is a fragmentary section through a 35 completed book bound in accordance with the present invention.

Referring in detail to the drawings, 10 indicates the leaves of a book which are independent and arranged in a pile or stack. As shown in Figure 40 1, these leaves are independent and unbound, either in the original state or forming part of a book from which the binding has been lost or removed. In the latter case, the back edges of the leaves are trimmed so as to remove any folds, glue 45 and the like and leave the back edges of the leaves in an even plane. A coat 11 of flexible glue is now applied to the back edges of the leaves 10, the pile of leaves having formed therein, by punching or drilling, a series of aligned elongated marginal slots 12 equally spaced from each other and 50 equally spaced from and parallel with the rear edge of the pile. A textile backing strip 13 is then applied to the glue layer 11, said strip being of a width corresponding to the thickness of the 55 pile of leaves 10 and of a length corresponding to

the length of the pile of leaves from top to bottom of the latter. When this has been accomplished, the pile of leaves is rounded as shown in Figure 2, and tapes 14 of buckram or the like are passed through the slots 12 with the ends thereof projecting at opposite sides of the pile of leaves as clearly shown. These projecting ends of the tape are then preferably folded over onto the outer face of the backing strip 13 and glued to the latter as shown clearly in Figure 3. A main or final 10 backing strip 15 similar to canton flannel or heavy super is then applied over and glued to the backing strip 13 and the glued down ends of tapes 14 as shown in Figure 4. This backing strip 15 is of a length corresponding to the length of the 15 back and of a width considerably greater than the thickness of the pile of leaves, so that it projects equally on both sides of the pile of leaves as at 15a. Finally, the projecting edges 15a of the 20 backing strip 15 are coated on the side away from the leaves with glue and attached to the front and rear cover portions of the binding proper 16, thereby completing the binding. It will be noted that the intermediate portion of the binding strip 15 is unattached to the back portion of the binding proper 16, and the tapes 14 are not strained 25 against the walls of the slots in any leaf of the book when the latter is opened, this construction permitting such leaves sufficient free relative movement as to insure that the leaves of the book 30 will lie substantially flat when the book is opened. Thus, the book bound in accordance with the present invention will withstand hard usage.

It is obvious that minor changes may be made in the form and construction of the invention 35 and in the particular steps and sequence of such steps in carrying out the invention as described herein, such as fairly fall within the spirit and scope of the invention as claimed.

What I claim as new is:

In a flat opening book, a stack of leaves provided with aligned uniformly spaced elongated slots adjacent the back edges thereof, a coating of flexible glue on the back edges of said stack of leaves, a backing strip adhered to and covering 45 said coating of glue, tapes extended through said slots and having the ends thereof folded over onto and glued to said backing strip, and a final backing strip applied over and glued to the first-named backing strip and the glued down ends of 50 said tapes, the last-named backing strip projecting at both sides of the pile of leaves for attachment to the front and rear cover portions of a binding proper.

WILLIAM DAVID PRICE. 55
